UNITED STATES PATENT OFFICE.

HARRIS P. HURST, OF SUMMIT, MISSISSIPPI.

BREECH-LOADING ORDNANCE.

SPECIFICATION forming part of Letters Patent No. 585,957, dated July 6, 1897.

Application filed July 28, 1892. Serial No. 441,433. (No model.)

To all whom it may concern:

Be it known that I, HARRIS P. HURST, a citizen of the United States, residing at Summit, in the county of Pike and State of Mississippi, have invented certain new and useful Improvements in Breech-Loading Ordnance; and I do hereby declare the following to be a full, clear, and exact description of the invention, such as will enable others skilled in the art to which it appertains to make and use the same.

This invention relates to breech-loading ordnance, particularly large-caliber guns.

Figure 1 is a longitudinal sectional view of a fifty-caliber eight-inch rifle embracing the main features of my invention. Fig. 2 is a similar view. Fig. 3 is an end view of the breech of the gun. Fig. 4 is a modification of the primary-charge tube and breech-block. Fig. 5 is a longitudinal sectional view of one form of sabot with the rear extension or telescopic primary-charge tube. Fig. 6 is a modification of Figs. 4 and 5 in which the breech-block carries the smaller of the two tubes. Fig. 7 is a cross-section of breech-support on a line $x-x$ of Fig. 2. Fig. 8 shows one form of fastening for primary-charge tube to the breech-block. Fig. 9 is a perspective of main charge, showing canvas covering and part of case.

Similar letters indicate corresponding parts.

Referring to the drawings, A represents the breech of the gun, and hinged thereto is the folding support or arm B, held in place by a strong bolt D, and on the inner face of the arm a recessed rail E extends from end to end, and a corresponding recessed cut F is made in one of the screw-interrupted sides of the breech-block G, whereby the breech-block, when it is unlocked, on being drawn rearward will slide on the rail until stopped by the bolt a, the rail dovetailing in the block preventing it from falling off, and is so arranged that the block will readily enter the breech when pushed forward, and a turn to the right locks the breech, which may be secured in any manner suitable to the style of the gun.

When the breech is open, the arm B is pushed back to a convenient loading position and the projectile H is placed in position in the gun, as shown in Fig. 1, with the

rotating band b forward of the slope of the powder-chamber c.

The primary charge I is placed, in whole or in part, in the tube J, the upper end of which is closed, and resting against or affixed thereto in any suitable manner is the sabot K, the under side of which may be cupped to form a gas-check d. The tube J may rest against the projectile without the sabot or may be affixed to the projectile before firing or become affixed thereto when fired by being driven into a hole in the bore of the projectile or over a tapering tailpiece thereon, as shown in dotted lines, Fig. 1.

The main charge L is arranged in a single package or series of packages in the form of rings e e and placed upon the primary-charge-receiving tube M, which may be placed in front of the breech-block or placed in it and extend through it, or made with it, or screwed into the head of the obturator f, or may be integral with it, or may extend through it, as shown in Fig. 4, and then it can be held in position in various ways, as by the key g, Fig. 8, which is pushed into the notch h of the end of the tube M, as illustrated in Fig. 4, or the tube M may be charged within and without and be fixed complete as a double-charged cartridge, and the lower end of tube M, when the cartridge is placed in the gun, would be seated and supported in the rear-extending primary-charge-tube-receiving chamber of the breech-block.

The lower end of tube J is cupped or reamed out until the edge is sharp, forming a gas-check N, or a notch or groove i may be cut on the outside of the end of tube J and filled with a soft-metal ring or other suitable packing as a gas-check, or a separate cup or open thimble may be driven over a coned or beveled end of tube J to prevent the flame from the primary charge from escaping until the gas-check N is free from the upper end of tube M.

The tube J, when it or tube M is charged, is pushed or telescoped partly or full length into tube M, and the arm being brought into line with the bore of the piece and resting on shelf O the breech-block is pushed into locking position, carrying with it the charges, as described, the tube J, with or without the sabot K, resting against the base of the pro-

jectile or the interposed crushable material K', dotted lines, Figs. 5 and 6. A one-sixth turn to the right secures the breech-block, and the gun is in position to fire, being loaded 5 with two charges of powder or other propelling material so separated as to permit the projectile to receive its initial impulse from the primary charge, the main charge only being fired while the projectile is well under 10 way along the bore of the gun.

When the gun is loaded, the arm E may be folded, as shown in dotted lines, Fig. 1, and full lines, Fig. 2, and secured in position by the catch o, and the manner of firing is as 15 follows: By any kind of a primer fire is communicated through the breech-block by the channel r (the interior end extending into the primary-charge tube M any desired distance) to the primary charge, and the gases 20 therefrom driving out the tube J, having thereon the sabot, which may be made to act as a cushion under the projectile by crushing up, thus reducing the chamber-pressure and increasing the velocity of the shot. By these 25 means, and particularly the starting of the projectile by the primary charge without much shock, enables me to fire a shell of five or six or more calibers in length filled with a large bursting charge of gun-cotton or other 30 high explosive and get it safely under way, the main charge being entirely separated from the primary or starting charge and is not fired until the lower end of tube J is free from the tube M. The flame from the primary 35 charge then communicates with and fires the main charge, but the projectile is moving rapidly, and there then being a large space between it and the main charge for the gases to expand in before the projectile is acted 40 upon by the main charge or second explosion the shock on the projectile is reduced to the minimum, and the chamber - pressure is greatly reduced even when the weight of the main charge is greatly in excess of and in 45 some guns more than double the maximum charge allowed in single-charge guns of this or any other class.

When the projectile is free of the gun, it is intended that the tube J, with or without the 50 sabot, separate from the projectile, though this is not essential in all cases. Means may be used to cause tube or sabot to separate or remain affixed to the projectile, as desired.

Any suitable form of gas-cups P may be 55 used on the breech-block, and the breech-block may be hollowed out, (dotted lines, Fig. 6,) so as to increase the volume of the primary charge. In heavy guns it may be necessary to band or jacket tube M to give it 60 great strength.

The rifling in guns firing a high-explosive projectile should begin some distance forward of the seat for the projectile, leaving a smooth bore for a considerable space for the project- 65 ile to get under way unimpeded, and in a double-charged gun this is very important. Until acted upon by the second explosion the

projectile should attain as much velocity as it is possible to give it, without great shock, from the primary charge.

The smaller tube may be attached to the breech-block, as shown in Fig. 6.

Many modifications may be made without departing from the letter and spirit and scope of my invention—as, for instance, in using a 75 very sensitive high explosive as a bursting charge for the projectiles a smooth-bore gun essentially charged as described herein, except using a cartridge or charge provided with a projectile having rotating wings or fins 80 thereon, as shown in Fig. 2 and described in the specification of application filed March 28, 1892, Serial No. 426,839, would be desirable—and I do not desire to limit myself to rifle-guns, but claim the construction for all classes 85 of guns to which it is capable of being applied.

What I claim is—

1. A breech-block for breech-loading guns provided with a separable primary-charge-carrying tube independent thereof and seated 90 and supported, when loaded, in a front-loading rear-extending chamber therein, substantially as described.

2. A breech-block for breech-loading guns having a front-loading, cartridge-receiving- 95 and-supporting, primary or starting charge chamber therein, the face of the breech-block supporting the main charge substantially as described.

3. In a breech - loading gun, the breech-block for closing the same having a rearwardly-extending chamber receiving therein the rear end or head of a primary-charge tube separate therefrom, a gas-check surrounding said tube forward of the face of said breech-block and a main charge forward of said gas-check, substantially as described.

4. In a breech - loading gun, the breech-block for closing the same having a primary-charge-carrying tube, a main charge without 110 said tube and an elongated subcaliber extension-body in said tube and extending forward and an independent body between the base of the projectile and said subcaliber-body, substantially as described.

5. In a breech - loading gun, the breech-block for closing the same having a primary-charge-carrying tube, a main charge without 115 said tube, said main charge consisting of a series of powder-sections held together by a suitable casing, substantially as described.

6. In a breech - loading gun, the breech-block for closing the same having a primary-charge-carrying tube telescoping with a tube 120 extending forward therefrom to a buffer or sabot carrying a gas - check thereon, and a main charge without said tube, substantially as described.

In testimony whereof I affix my signature in presence of two witnesses.
